I. H. STEVEN.

COMBINED ELECTRIC FIXTURE SUPPORT COUPLING AND ELECTRIC CONNECTOR THEREFOR.
APPLICATION FILED MAR. 6, 1918.

1,323,114.

Patented Nov. 25, 1919.

UNITED STATES PATENT OFFICE.

IAN HECTOR STEVEN, OF TORONTO, ONTARIO, CANADA.

COMBINED ELECTRIC-FIXTURE SUPPORT-COUPING AND ELECTRIC CONNECTOR THEREFOR.

1,323,114.

Specification of Letters Patent. Patented Nov. 25, 1919.

Application filed March 6, 1918. Serial No. 220,812.

To all whom it may concern:

Be it known that I, IAN HECTOR STEVEN, of the city of Toronto, county of York, Province of Ontario, Canada, have invented certain new and useful Improvements in Combined Electric-Fixture Support-Couplings and Electric Connectors Therefor, of which the following is a specification.

My invention relates to improvements in combined electric - fixture support - coupler and electric-connector therefor, and the objects of my invention are: firstly, to provide standardized means whereby suspended electric fixtures can be coupled to, and un-15 coupled from, a suitable electric receptacle, mounted in a wall or ceiling for example, without interfering with the wiring, thus not only saving much time, but also preventing the injury of the electric wires in the 20 walls and ceilings in buildings; secondly, to provide an improved type of plug, and socket, which can be mounted within a comparatively shallow wall- or ceiling-box, and whereby my broad idea can be economically 25 and safely put into practice, and an embodiment within my invention will be hereinafter particularly set forth, and what I claim as new will be pointed out in the claims forming part of this specification.

Figure 1 is a perspective view of a suitable type of housing or wall-box, embodying a certain important part of my invention, showing the same mounted in a wall, portion of which is shown. Fig. 2 is a plan view 35 of the housing or wall-box with the cover removed. Fig. 3 is a vertical cross section on the line 3—3, Fig. 2. Fig. 4 is a vertical cross section on the line 4—4, Fig. 2. This figure also shows, in dotted position, a plug 40 carried by the electric device designed to be coupled to the wire in a building. Fig. 5 is a plan view of the plug-receptacle. Fig. 6 is a vertical central longitudinal section through the plug showing, in section, portion 45 of the housing or wall-box supporting the same, and portion of the electric device to which the plug is coupled. Fig. 7 is a horizontal cross section on the line 7—7, Fig. 6. Fig. 8 is a bottom plan of the plug. Fig. 50 9 is a plan of the bushing which receives the plug. Fig. 10 is a fragmentary vertical section on the line 10—10, Fig. 9. Figs. 11 and 12 are side elevations of opposite sides of the bushing illustrated in Fig. 9, and Fig.

13 is a perspective view of a suitable contact member carried by the plug receptacle. 55

In the drawings, like characters of reference refer to the same parts.

No standardized means has heretofore been developed whereby it is possible to 60 couple any size or weight of electric fixture to the box mounted in a ceiling or wall containing the terminals of the wires leading from the outside, by the very act of screwing said fixture into said box. It is one of 65 the objects of my invention to provide standardized means whereby an electric fixture of any size or weight can be readily unscrewed from its supporting box and as readily screwed into another supporting box, without the necessity of having to cut the wires connecting the same with the wires in the building. Where electric fixtures have been coupled to the ordinary wall-box and removed therefrom several times, the terminal 70 wires in the building become so short that in some cases new wiring has to be installed. Oftentimes as a result of the constant placing and removal of electric fixtures, the walls and ceilings are considerably damaged. 75 Now by means of my invention, no possible damage can be done to walls and ceilings, nor to the terminal wires mounted therein, and one of the great advantages flowing from my invention resides in the fact that 80 since the use of the same removes all necessity of having to interfere in any manner whatsoever with the terminals of the wiring in walls and ceilings, a common source of fire caused by arcing is absolutely removed. 85

In my preferred form of invention, I provide a nipple comprising an externally-threaded portion, the external diameter of which, together with the pitch of the thread, are of standard dimensions; an internally-threaded portion, the diameter of the bore of which will vary according to the diameter of the coupling element of the electric fixture to be screwed thereinto, and an external shoulder or stop designed to fit against the 100 outer end of an internally-threaded coupling carried by the wall- or ceiling-box and designed to receive the said externally-threaded portion of said nipple. A suitable plug is carried by said nipple to which the wires 105 of the electric fixtures are connected so as to provide suitable contact terminals so that by the very act of screwing said nipple into a

wall-box, electric connection will be made with a suitable receptacle mounted in said wall-box and provided with terminals connected with the wiring of the building.

5 The diameter of the coupling element of the electric fixture to be screwed into the internally-threaded portion of the nipple will vary according to the weight of the fixture and the practice of different manufacturers. When the fixture is a heavy one, this coupling element (which is invariably in the form of a pipe or tube) will necessarily be of greater diameter than when the fixture is a small light one, and, therefore, 10 it will be understood that the diameter of the bore of said internally-threaded portion will vary in different nipples, but since the nipple is designed to be carried by the coupling element or pipe of the fixture, this 15 fact will not in any wise interfere with the standardization in size of the externally-threaded portion of said nipple and the internally-threaded bore of the coupling carried by the wall- or ceiling box. No matter 20 whether the electric fixture to which the nipple is coupled be a heavy or a light one, the standardization of the coupling portion will permit this electric fixture to be coupled to, and uncoupled from, the standardized 25 coupling-element of the wall- or ceiling-box, no matter where located.

The location of the internally-threaded coupling element of the wall- or ceiling-box, hereinafter particularly described, enables 30 me to secure a firm strong coupling for the nipple, without having to increase the depth of the wall- or ceiling-box, and further without unduly increasing the thickness of the cover of the wall- or ceiling-box carrying 35 said coupling.

39 is a nipple composed of an externally-threaded portion *m* and an internally-threaded portion 100. An external flange or stop *O* is carried by said nipple and is 40 designed to seat against the coupling 18 carried by the cover *B* of the housing or wall-box *A*. The said cover is preferably positioned flush with the outer surface of the wall, and is carried by said box by any suitable means such as screws *C*, screwed into lugs *D* secured to, or formed a part of, said housing. The portion *m* of the nipple 39 screws into the internally-threaded coupling 18. The upper portion 100 of said 45 nipple is internally-threaded so as to receive the externally-threaded part 42 of the fixture. The external diameter and the pitch of the thread of the portion *m* of the nipple 39, as well as the internal diameter and 50 pitch of the thread of the coupling 18 are of standard dimensions so that a fixture supplied with the nipple 39, irrespective of the weight and size of the fixture, may be coupled to, and uncoupled from, the box 55 *A*. The advantages derived from the dis-

closure just made are many and are very important.

Any suitable type of plug and plug-receptacle may be used with my broad conception, and I shall now describe the preferred plug used, and coupled to the nipple 39. The upper end 40 of the body portion 19 of the plug, which is made of porcelain or equivalent material, is preferably housed within the externally-threaded portion *m* of the nipple, and is secured in place by any suitable means such as a grub-screw 41, held in said portion *m* and extending into the hole or pocket *n* formed in said end 40. This plug is chambered as shown at 20, and each side of the lower portion of the body thereof is slotted as shown at 21 to provide communication with said chamber. 22 is a bridge-wall connecting the sides of the lower portion of the body portion 19 together so as to make a strong construction. The lower portion of this bridge-wall is provided with a socket 23 which communicates with a passage-way 24 which is formed through said wall 22. The socket 23 is preferably tapered and receives the tapered neck 44 secured to, or formed a part of, a plug 25 made of porcelain or equivalent material. This plug is provided with a passage-way 26 therethrough aligned with the passage-way 24, and held in said passage-way is a screw 27, threaded on its inner end so as to screw into the plate 28, which is held thereby against the inner end of the wall 22. This screw also binds the plug 25 firmly in place. 100 By means of the screw 29, screwing into the extension 30 of the plate 28, one of the wires 31 of the fixture is coupled to this plate. 32 is a circular metal plate provided with a central opening 33, through which extends the neck 44. Struck from this plate is a lip 34 which carries the screw 35 by means of which the other fixture-wire 36 is coupled to said plate 32. 37 is a washer of any suitable insulating material 110 interposed between the plate 32 and the inner end of the plug so as to insulate the plate 32 from the plate 28 and its extension 30. 38 is a metal contact plate secured by the screw 27 to project beyond the end of 115 the plug 25.

Mounted within the housing *A* is the plug-receptacle *E* of the preferred construction which I shall now describe. This plug-receptacle is secured in place by screws or equivalent means *F*. 2 is a central chamber formed in the plug receptacle *E* (which is made of porcelain or equivalent material) to receive the bushing 3, (also made of porcelain or equivalent material). 4 is a 120 circular contact plate and the same rests upon the annular shoulder 6 formed in the bushing 3. Secured to or formed a part of the plate 4 is an extension 7 forming a binding-post which carries a binding-screw 8. 9 125 130

is one of the wires mounted in the wall or ceiling and coupled to said binding-post. One side of the bushing 3 is provided with an opening 10 through which extends the 5 extension 7 of the plate 4. This extension is preferably shaped as shown so as to hug the side of the bushing 3 and economize in space. 11 is a metal contact plate located within the chamber 2 and positioned below the plate 4. Preferably integrally formed with the plate 11 is an extension 12 which carries a binding-screw 13 thus forming a binding-post to which is coupled the wire 14. The sides of the plug receptacle E are 10 slotted as shown at 15 so as to permit of the ready access to, and manipulation of, the binding-posts already mentioned. By means of the screws 16 and 17 held in suitable holes formed in the plug receptacle E, 15 and screwing respectively into the contact plate 4 and plate 11, these parts are firmly held in position. Integrally formed with the plug receptacle E, is a shoulder α through which passes the screw 16. This 20 shoulder, it will be apparent upon referring to Fig. 5, projects well toward the center of the said receptacle, and portion of the circular plate 4 rests thereagainst. This shoulder is for the purpose of insuring the complete 25 insulation of the plate 4 from the contact-plate 11.

When the plug, carried by the member 42 of the fixture, is screwed into the coupling 18 and so housed within the box A, the 30 plate 32 makes contact with the circular plate 4, and as this circular plate is provided with a central opening b to permit the plug 25 to pass therethrough, the plate 38 comes into contact with the plate 11 thus completing 35 the necessary contact between the plug and its receptacle. It will be understood that the current will have a free path through the wire 14; plates 11 and 38 and screw 27; plate 28 and wire 31, and return 40 through the wire 36; lip 34; plate 32; plate 4, and the wire 9.

The sides of the bushing 3 are preferably recessed as shown at c and d so as to more or less house the extensions 7 and 12 thereby 45 insuring compactness.

It will be understood that the bushing 3 can be readily removed from the plug receptacle E, when desired.

The plug and plug-receptacle, already described, are comparatively cheap to manufacture, and since they are efficient in all necessary respects, I prefer to use them with the standardized coupling means before described, though I do not confine myself in 55 my broad claims to the use of the plug and receptacle.

By one skilled in this art, it will be understood that the two poles of the plug are brought into union with the two poles 60 of the plug receptacle E through a rotary

movement, thus insuring absolute contact between these poles.

It will be observed that to carry out my idea, the diameter of the body portion 19 of the plug beyond the portion m must be sufficiently smaller than the diameter of the bore of the coupling 18 so as to permit this portion of the plug-body to be freely passed through said coupling. 70

It will, also, be understood that the diameter of the plug 25 carrying the plate 38 must be smaller than the distance separating the inner vertical face of the shoulder α from the opposite side of the bushing 3 so that the plate 38 may make positive contact 80 with the plate 11, while the plate 32 is free to make contact with the plate 4. 75

Should occasion arise, the nipple 39, attached to the element 42 of the fixture, can be removed from this element and retapped 85 to be coupled to the coupling element of another electric fixture, and without in any manner interfering with the standardization of the other parts of the nipple.

In this specification, and the claims forming part thereof, in respect of my preferred form of invention, the term "non-standardized" is used to mean that the threaded portion of a finished nipple or coupler, whereby the threaded member of an electric fixture 90 has union therewith, varies in diameter in different nipples, and the term "standardized" is used to mean that the threaded portion of a finished nipple or coupler which has union with the coupling element of a 95 cover or wall-box, is of standard size so that any given nipple or coupler may be unscrewed from any wall-box and screwed into another wall-box. 100

Claims:

1. The combination of a housing or wall-box having a bottom wall and provided with an apertured removable cover; a chambered plug-receptacle secured to said bottom wall entirely within said wall-box with the chamber thereof in alignment with the aperture in the removable cover of said wall-box; a pair of insulated electric terminals carried by said receptacle and extending into the chamber thereof; a plug comprising a body portion made of insulating material, positioned within the chamber of said plug-receptacle through the aperture of said removable cover; a pair of insulated electric terminals carried by said plug and designed 110 to make contact respectively with the terminals extending into the chamber of said plug receptacle; an electric fixture, and coupling means whereby said plug is removably coupled to said housing or wall-box cover, 115 and to said electric fixture. 120
2. The combination of a housing or wall-box having a removable cover provided with an internally-threaded aperture therethrough; a chambered plug-receptacle se- 130

cured to and entirely within said wall-box with the chamber thereof in alinement with the aperture in the cover of said wall-box; a pair of insulated electric terminals carried by said receptacle and extending into the chamber thereof; a plug comprising a body portion made of insulating material, positioned within the chamber of said plug-receptacle through the aperture of said cover; 5 a pair of insulated electric terminals carried by said plug and designed to make contact respectively with the terminals extending into the chamber of said plug receptacle; an electric fixture; a tubular coupler carrying 10 said plug, and having an inner externally threaded portion to screw into the internally-threaded aperture of said cover, said coupler having an outer internally threaded portion into which said fixture is screwed. 15 20 3. The combination of a housing or wall-box provided with an apertured cover; a chambered plug-receptacle secured to and entirely within said wall-box with the chamber thereof in alinement with the aperture in the cover of said wall-box; a pair of spaced superposed contact plates forming two poles extending into the chamber of said plug-receptacle; means whereby electrical connection is made with said plates; a removable 25 insulating bushing mounted in the chamber in the said plug-receptacle and carrying said plates; a plug comprising a body portion made of insulating material positioned within the chamber of said plug-receptacle 30 35 through the aperture of said cover; a pair of insulated electric terminals positioned one beyond the other and carried by said plug, and designed to make contact respectively with the plates extending into the chamber 40 of said plug receptacle; an electric fixture, and coupling means whereby said plug is removably coupled to said housing or wall-box cover, and to said electric fixture. 4. The combination of a plug comprising a 45 chambered portion and a tubular portion projecting therebeyond, the diameter of the chambered portion being greater than the diameter of said tubular portion; means held in said tubular portion in order to fixedly 50 connect the same with said chambered portion; a centrally-apertured contact-plate positioned at the end of said chambered portion and projecting beyond the sides of said tubular portion; a contact-plate carried by 55 the end of said tubular portion and of smaller diameter than the same; binding posts whereby electric connection is had respectively with said contact plates; a centrally-chambered plug-receptacle made of insulating 60 material; a tubular bushing made of insulating material mounted within said plug receptacle, and provided interiorly with a horizontal annular shoulder, and further provided with an opening in one side there- 65 of; a centrally apertured contact-plate seat-

ed against said annular shoulder and provided with a binding-post which projects through the opening in the side of said bushing; another contact-plate positioned at the bottom of the chamber in said receptacle 70 and extending upwardly between said receptacle and said bushing to form a binding-post; the contact plates of said plug making contact with the contact plates of said receptacle when the plug is inserted therein, as 75 set forth.

5. A plug for plug receptacles of wall boxes comprising a chambered portion and a tubular portion projecting therebeyond, the diameter of the chambered portion being 80 greater than the diameter of said tubular portion and said chambered portion having a transverse rigid-bridge wall; means held in said tubular portion and bridge wall in order to fixedly connect the former with 85 said chambered portion; a centrally apertured contact-plate positioned at the end of said chambered portion and projecting beyond the sides of said tubular portion; a contact plate carried by the end of said tubular portion, and binding-posts carried by said chambered portion bridge wall whereby 90 electric connection is had respectively with said contact plates.

6. A receiving member for a plug comprising a centrally-chambered receptacle made of insulating material; a bore-provided bushing made of insulating material designed to be mounted in the chamber of said receptacle, and provided at one side 95 with an opening; an annular horizontal shoulder formed within said bushing; a circular centrally-apertured metal plate positioned on the shoulder of said bushing; a binding-post, forming part of said plate, 100 projecting through the opening formed in the side of said bushing; another plate positioned in the bottom of the chamber of said receptacle and extending into the bore thereof; a binding-post forming part of said 105 second-mentioned plate and extending upwardly between one side of said bushing and said receptacle, and means whereby 110 said plates are secured in position.

7. A receiving member for a plug comprising a centrally-chambered receptacle made of insulating material; a shoulder integrally formed with said receptacle and projecting toward the center thereof; a bore-provided bushing made of insulating material 115 designed to be mounted in the chamber of said receptacle, and provided at one side with an opening; an annular horizontal shoulder formed within said bushing; a circular centrally-apertured metal plate positioned on the shoulder of said bushing and against the shoulder of said receptacle; a binding-post forming part of said plate projecting through the opening formed in the 120 side of said bushing; another plate posi- 125 tioned on the shoulder of said bushing and against the shoulder of said receptacle; a binding-post forming part of said plate projecting through the opening formed in the side of said bushing; another plate posi- 130

- tioned in the bottom of the chamber of said receptacle and extending into the bore thereof; a binding-post forming part of said second-mentioned plate and extending upwardly between one side of said bushing and said receptacle, and means whereby said plates are secured in position.
8. A coupling plug comprising a body portion made of insulating material having a central bore therethrough and further provided at each side with a slot each of which communicate with the said bore; two contact plates, one of greater diameter than the other and positioned one beyond the other; means whereby said contact plates are coupled to said body portion and insulated therefrom, and means whereby electrical connection is had with said contact plates.
10. 9. A coupling plug comprising a body portion made of insulating material having a central bore therethrough and further provided at each side with a slot, each of which communicate with said bore; two contact plates, one of greater diameter than the other and positioned one beyond the other; means whereby said contact plates are coupled to said body portion and insulated therefrom; means whereby electrical connection is had with said contact plates, and a coupling element carried by one end of said body portion.
10. The combination of a housing or wall-box provided with an apertured cover; a centrally chambered plug receptacle secured within said wall-box with the chamber thereof in alinement with the aperture in the cover of said wall-box; a pair of plates forming two poles extending into the chamber of said plug receptacle and having extensions whereby electrical connection is made therewith, and a removable insulating

bushing mounted in the chamber in said plug receptacle so as to insulate said plates.

11. In combination, a wall box having a chambered contact carrying plug receptacle fixedly secured entirely therein and provided with an opening in one wall thereof alined with the plug receptacle chamber, a contact carrying plug removably and rotatably received in the chamber of said plug receptacle through said opening in the wall box with the contacts thereof engaged with the contact of the plug receptacle, and a one-piece coupler directly carrying said plug and having standard means for detachably connecting the same directly to the wall box with the attached plug operatively arranged in the plug receptacle chamber, the coupler having a non-standardized means for detachably connecting an electric fixture member thereto.

12. In combination, a wall box having a chambered contact carrying plug receptacle fixedly secured entirely therein and provided with an internally threaded opening in one wall thereof alined with the plug receptacle chamber, a contact carrying plug removably and rotatably received in the chamber of said plug receptacle through said opening in the wall box with the contacts thereof engaged with the contacts of the plug receptacle, and a one-piece coupler directly carrying said plug and having a standard externally threaded inner end for threaded reception in the threaded wall box opening to detachably connect the same to the wall box with the attached plug thereof operatively arranged in the plug receptacle chamber, the coupler having a non-standardized internally threaded outer end for detachably connecting an electric fixture member thereto.

IAN HECTOR STEVEN.
